INVENTOR.
MARY FROST ARTZ

BY
Parker + Burton

ATTORNEY.

UNITED STATES PATENT OFFICE.

MARY FROST ARTZ, OF DETROIT, MICHIGAN.

OVERSHOE.

Application filed September 21, 1925. Serial No. 57,587.

My invention relates to an improved overshoe intended particularly to be worn over a lady's evening slipper.

The object is to provide an overshoe of light weight waterproof construction for wear over a dress slipper, which overshoe is of such a character as to conform closely to the shape of the slipper covered thereby and exhibit the graceful outline and decorative coloration thereof while completely protecting the same from exposure.

It presents a neat, attractive appearance and serves as an effectual covering for the most delicate shoe. It is provided with a serviceable sole and a top portion extending upwardly therefrom adapted to be fastened snugly and in a slightly manner about the ankle of the wearer. This top structure is of thin transparent or translucent material, which renders visible the shoe over which it is worn while adding the minimum amount of warmth which permits wear of the overshoe indoors, as at the theatre, without discomfort.

The above objects and meritorious features together with other important advantages of my invention will more fully appear from the following specification, appended claims and accompanying drawing, in

which:

Figure 1 is an elevation of my overshoe in use.

Fig. 2 is an elevation of the same overshoe removed from the foot.

Fig. 3 is an elevation of a modified form of my invention.

Fig. 4 is a vertical sectional view taken on the line 4—4, Fig. 2.

Fig. 5 is a cross-sectional view taken on line 5—5, Fig. 3.

My improved overshoe provides a protective covering for a lady's evening slipper at once serviceable and of pleasing appearance. The sole 10 is preferably formed of rubber or other suitable material of sufficient strength and thickness to serve its purpose. Secured to the sole in a suitable manner is a top structure 12 of thin substantially transparent or translucent material such as "thin transparent rubber" which will conform closely to the outline of the shoe, provide a minimum amount of warmth and render visible the shoe 14 covered thereby. By the term "thin transparent rubber" I mean to include rubber of this character whether

reinforced or unreinforced by thin fabric. A common construction is rubber coated or impregnated fabric. Thin silk or other similar material is commonly employed for this purpose, and after it has been treated the resulting product is practically transparent or at least translucent.

Slippers for dress and evening wear are of delicate construction. Materials employed in their manufacture are frequently such that a single exposure to snow or water on the street or pavement will ruin them. They are expensive and yet it is impossible at the present time to protect them from exposure without employing overshoes of the galosh type, which are heavy, hot and unsightly in appearance.

The top structure of my overshoe is substantially transparent and when I employ this term throughout the specification and claims I intend the same to designate materials of a translucent or diaphanous character, which while not strictly transparent render visible the slipper covered by my overshoe.

In Figs. 1, 2 and 4, I have illustrated an overshoe of this kind which has a top of thin transparent rubber, or rubber-coated, thin, diaphanous fabric.

In Figs. 3 and 5, I have illustrated a slightly modified form of my invention, the top structure having a lining 16 which may be of thin gauze or sheer silk providing a smooth surface that will slip readily over the shoe. The outer covering is of thin transparent rubber or similar waterproof material as above set forth.

In order that the top of my overshoe may fit snugly about the ankle, I prefer to provide on each side a gusset 18 fitted with suitable fasteners 20 whereby it may be secured in the folded-over position as appears in Fig. 1.

This top material of my overshoe may be furnished in different colors to blend harmoniously with the shade of the dress slipper over which the same is worn and which is visible therethrough.

What I claim is:

1. An overshoe having a sole and a top structure of thin diaphanous water-proofed fabric through which the shoe covered thereby is visible.
2. An overshoe having a sole and a top structure extending upwardly therefrom

thin substantially transparent waterproof material which renders visible the shoe covered thereby.

3. An overshoe having a sole and a top structure of relatively thin flexible substantially transparent waterproof material extending upwardly therefrom to a point above the ankle of the wearer, which top structure is adapted to conform to the structural outline of the shoe enclosed thereby and to render the same visible therethrough.
4. An overshoe having a sole and a top structure extending upwardly therefrom of thin waterproof material provided on each side adjacent its upper edge with a gusset ¹⁵ adapted to be folded over to fit snugly about the ankle of the wearer and having fastening means to secure the same in such folded-over relationship.

In testimony whereof, I sign this specification.

MARY FROST ARTZ.
